UNITED STATES PATENT OFFICE

2,570,620

MARKING GAUGE FOR PLOWSHARES

Lee O. Wiese, Perry, Iowa

Application October 19, 1949, Serial No. 122,278

3 Claims. (CL. 33—174)

1

This invention relates to a gage or template, to be easily and quickly applied to a plow share, and when so applied provide a guide whereby lines may be easily and quickly drawn on the plow share to indicate a path to be followed by a cutting torch or tool, for severing from the share its worn point and cutting edge, for the purpose of substituting new parts.

The object of my invention is to provide a marking gage that may be easily and quickly applied to plow shares of different shapes and sizes with a comparatively small amount of adjustment, and when so applied provide means whereby lines may be drawn on the share properly located and positioned relative to the back edge of the share, to serve as cutting guides for the removal of worn portions of the share, whereby new replacement parts may be easily and quickly placed in proper operative positions to be fixed to the share by welding even if the share has been badly worn. More specifically, it is the object of my invention to provide a marking gage having a portion adapted to be supported on the upper face of the forward edge of the share, by means of which a line may be drawn substantially parallel with the back edge of the share and near its cutting edge, and a second marking portion, adjustably mounted to the first marking portion, adapted to rest against the outer surface of the upper edge of the land side of the share by means of which a line may be drawn on the land side near its upper edge, whereby the gage may be easily and quickly applied to shares having land sides mounted in planes at various angles relative to its cutting edge.

My invention consists in the construction, arrangement and combination of the various parts of the device whereby the objects contemplated and attained as hereinafter more fully set forth, pointed out in my claims and illustrated in the accompanying drawings, in which:

Figure 1 is a perspective view of my improved marking gage.

Figure 2 is a perspective view showing my improved gage as applied to a worn plow share.

Figure 3 is an end elevation of the marking gage as applied to a plow share having a long point.

Figure 4 is a similar view showing the gage applied to a share having a short point.

Figure 5 is a perspective view of a worn plow share showing lines drawn thereon by means of my marking gage, to provide guide lines for cutting the worn parts from the share.

Figure 6 is a front view of a plow share after the worn parts have been removed.

2

Figure 7 is an end elevation of Figure 6.

Figure 8 is an end elevation of a worn plow share showing in dotted lines the relative position of a repair point as applied to a worn plow share.

Referring to Figure 5 the numeral 10 indicates the body of a plow share, 11 the landside portion, 12 the worn cutting edge and 13 the worn point. In Figure 8 that portion of the plow share worn away is indicated by dotted lines 14. The dotted lines 14, 15, 16 and 17 represent the end of a replacement point to be applied after the worn parts have been removed. The lines 18, 19, 20 and 21 of Figure 5 are to be followed by a cutting torch for the removal of the worn parts 12 and 13, the share then having the form illustrated in Figure 6.

Plow shares now in common use are made in several lengths, the landside portions of which are also set at various angles relative to the back edge of the share.

My improved marking gage comprises an element 22 adapted to be mounted adjacent to the outside face of the landside 11 to provide a guide for drawing the lines 20 and 21; and a second element 23 for drawing the lines 18, 19 and 24. The element 22 comprises an angular plate having a flange 26 adapted to be placed against the outer surface of the landside 11 and a flange 27 to rest on top of the adjacent end of the share body, as illustrated in Figure 2, said element being curved downwardly at its center to fit the contour of the upper edge of the landside of a new share, the forward end of the member 26 having its lower edge provided with a notch 28 to provide a marking edge 29. The forward end of the element 22 serving to provide a guide for drawing the lines 21 and 24 while the edge 29 provides a guide for drawing the line 20. The distance between the edge 29 and the under surface of the member 27 being equal to the thickness of the back flange of the repair point to be applied, and represented by the dotted lines 14 and 17 of Figure 8. When the element 22 is applied to plow shares having points of standard lengths the back end 31 of the element is adjusted to position even with the back edge of the share, but when applied to shares having shorter points, the element 22 is adjusted with the pin 32 against the back edge of the share, as illustrated in Figure 4. The pin 32 is mounted on a spring 33 the lower end of which is fixed to the body of the member 27, the pin being pressed through an opening 34 when used as a gage.

For drawing the marks 18 and 19 I have formed on the inner edge of the element 27 a latterly pro-

jecting plate 36 the lower edge 37 of which provides a guide for drawing the line 19. Pivotally mounted in the plate 36 is one end of a rod 35 the inner portion of which is slightly curved at 38, the outer end of the curve terminating in a straight portion 39 adapted to be mounted substantially parallel with the back edge of the share, the back end of the rod 35 is provided with a rearwardly and inwardly extending portion 40 having a hook 41 at its back end to serve as a stop to engage the back edge of the share to support the rod 35 at the proper distance from the back edge of the share body. A sleeve 42 is rotatably mounted on the back end of the member 40 to serve as a stop when the gage is applied to shares having short points. The front end of the sleeve 42 has a lug 43 to be turned downwardly when used as a stop and at the time the pin 32 is used as a stop. A brace 44 is provided for stiffening the member 40. The plate 36 is formed with an opening 45 for pivotally receiving the inner end of the rod 35 at times when the gage is used to draw lines for short points.

The use and application of my gage is simple, the worn plow share is placed on a suitable surface plate or table; if the share is one having a long point the angular element 22 is placed on top of the landside portion with the flange 26 adjacent to the vertical outer vertical face of the landside and with the back end of the flange 27 held firmly on top of the landside portion of the share and with its back end even with the back edge of the share. The hook 39 is then placed over the back edge of the share with the rod 35 adjacent to the upper face of the share near its front edge. A line 18 may then be drawn along either the front or back side of the rod 35 by means of chalk or any other suitable instrument. A line may then be drawn along the front edge 37 of the plate 36, lines 24, 21 and 20 may then be drawn along the front end of the member 27 and along the edge 29 of the member 26.

If the gage is to be applied to a share having a short point the inner end of the rod 35 is inserted in the opening 45, the sleeve 42 is then rotated to move the lug 43 to extend downwardly, the pin 32 is also pressed down through the hole 34, the gage is then placed in position as before described with the lug 43 and the pin 32 against the back edge of the share, the above described lines may then be drawn. By pivotally connecting the rod 35 to the plate 36 it will be seen that the gage is adapted to fit plow shares of various sizes and shapes and more particularly to those wherein the landsides of one share is set at a different angle relative to the back edge of the share than that of another share. By forming the under surface of the flange 27 to the same contour as that of the top edge of a share before it has been worn means is provided for accurately drawing the line 20 regardless of the amount the point and the upper edge of the landside portion has been worn, since the forward end of the member 22 is supported to the proper elevation by the back end being held firmly on the unworn portion of the upper edge of the landside portion, as shown in Figure 3.

Thus it will be seen that I have provided a marking gage for worn plow shares of simple, durable and inexpensive construction which may be easily

and quickly applied and when so applied provide means whereby both the cutting edge and the forward end of the landside portion may be marked with one setting of the gage.

5 I claim:

1. A gage to serve as a guide for marking a worn plow share and its landside portion to provide lines for the removal of its worn point and cutting edge, comprising, a substantially horizontal and elongated body including front and back ends, inside and outside edges, the inside edge including an extension having a forwardly and inwardly inclined marking edge, the outer edge of said body terminating in a downwardly extending flange, a marking rod having one end pivoted to said extension to swing in a substantially horizontal plane, the free end of said rod having a rearwardly extending extension.

2. A gage to serve as a guide for marking a worn plow share and its landside portion to provide lines for the removal of its worn point and cutting edge, comprising, a substantially horizontal and elongated body including front and back ends, inside and outside edges, the inside edge including an extension having a forwardly and inwardly inclined marking edge the outer edge of said body terminating in a downwardly extending flange, a marker rod having one end pivoted to said extension to swing in a substantially horizontal plane, the free end of said rod having a rearwardly extending extension, having its free end terminating in a plurality of stop devices, and a movable stop device mounted on and near the back end of said body.

3. A gage to serve as a guide for marking a worn plow share and its landside portion to provide lines for the removal of its worn point and cutting edge, comprising, an elongated body including back and front ends also inside and outside edges, the outside edge having a downwardly extending flange, the inner edge including a forwardly and inwardly inclined extension provided with a plurality of pivot openings, a marker rod having one end adapted to be pivotally mounted

45 in any of said openings, the other end of said rod terminating in a rearwardly extending portion, a stop device supported by the free end of said portion, and a movable stop device mounted on and near the back end of said elongated body, 50 said body being adapted to be placed on the upper surface of the landside portion of a plow share with its stop device engaging the back edge of a plow share, with its front edge terminating near the point end of the share and with the downwardly extending flange adjoining the landside 55 of the share for locating the elements of the gage whereby, the lower edge of the front end of said flange, the front end of said body, the front edge of said inclined extension and said rod will 60 serve as marking guides.
